227,361

DEPTH CONTROL FOR A TROLLED FISHING LURE

Max E. Kleman, 4750 Franklin Blvd.,
Eugene, Oreg. 97405

Filed Dec. 27, 1971, Ser. No. 212,889

Term of patent 14 years

Int. Cl. D22—05

U.S. CL. D22—30

FIG. 1 is a side elevational view of a depth control for a trolled fishing lure showing my new design,

FIG. 2 is a front elevational view of the invention,

FIG. 3 is a rear elevational view of the invention,

FIG. 4 is a plan view, and

FIG. 5 is a bottom plan view of the depth control.

I claim:

The ornamental design for a depth control for a trolled fishing lure, as shown.
